(57) **CLAIM**

I claim the ornamental design for a dent removing sheet metal hammer attachment for air gun, as shown and described.

DESCRIPTION

FIG. 1 is a perspective view of a dent removing sheet metal hammer attachment for air gun showing my new design; FIG. 2 is a side elevational view thereof, the elevational view of the opposing side being a mirror image thereof; FIG. 3 is an end elevational view thereof, the elevational view of the opposing end being identical thereto; FIG. 4 is a top plan view thereof; FIG. 5 is a bottom plan view thereof; and, FIG. 6 is a reduced perspective view showing the dent removing sheet metal hammer attachment for air gun in use; the broken lines depict environmental structure for illustrative purposes only and form no part of the claimed design.
